UNITED STATES PATENT OFFICE.

PAUL J. KAMPER, OF SIOUX CITY, IOWA.

HAND-CAR.

SPECIFICATION forming part of Letters Patent No. 787,381, dated April 18, 1905.

Application filed August 24, 1904. Serial No. 222,001.

To all whom it may concern:

Be it known that I, PAUL J. KAMPER, a citizen of the United States, residing at Sioux City, in the county of Woodbury and State of Iowa, have invented new and useful Improvements in Hand-Cars, of which the following is a specification.

This invention relates to a hand-car of the manually-operated type, and has particular reference to the actuating mechanism to overcome numerous disadvantages heretofore encountered in devices of this class.

One of the special features of construction in the present invention is the adaptability of application thereof to hand-cars now in use through the medium of adjustable means consisting of a screw-threaded connection between the primary actuating means and the driving device to accommodate a variation in vertical extent of the gallows with respect to the main driving or master gear, thus providing for economy in the substitution of the several parts in the event of wear by reason of the fact that a new rack-bar only will be required to be replaced or applied in old constructions without affecting the usefulness or practical operation of the driving mechanism controlled by the said rack-bar. In the present instance a double rack-bar is used, or, in other words, a bar having rack-teeth on opposite sides, and the latter is adjustably connected to take up wear with a crank attachment for operating the master-gear. Meshing with the rack-bar are specially-constructed reversible gears or actuating elements which may be turned or revolved in their supporting means to bring new surfaces or parts in coöperation with the opposite teeth of the rack-bar, and thereby prolong the service of the said primary mechanism. The gear elements in the present construction are inclosed by or held between head-disks, to which operating-levers or hand-bars are attached, and the advantage derived, from an economical standpoint, in this direction is that the said head-disks may be released from the gear elements and the latter turned to bring new portions thereof in connection with the rack-bar and at the same time confine the rack-bar in accurate registration with

the teeth of the gear elements and thus insure a positive actuation of the main or master gear. By the present construction and arrangement of rack-bar and actuating-gear operatives and those occupying the hand-car 55 will be protected from injury in view of the fact that the rack-bar is guarded or held between the head-disks and in such position with respect to the gallows in such manner as to prevent engagement with the clothing or 60 body parts of those adjacent thereto.

In the drawings, Figure 1 is a side elevation of a hand-car embodying the features of the invention. Fig. 2 is a longitudinal vertical section of the same. Fig. 3 is a detail perspective view of one of the hand-bars and the head-disks attached thereto. Fig. 4 is a detail perspective view of one of the gear elements, which is reversibly disposed in the hand-bars.

Similar numerals of reference are employed to indicate corresponding parts in the several views.

The numeral 1 designates a hand-car frame of the usual construction, but in the present instance is preferably formed with side and end bars 2 and 3, an intermediate cross-bar 4, and longitudinal supporting-bars 5. In suitable bearings 6, secured to the side bars, rotatable axles 7 are mounted and have thereon track-wheels 8. The one axle has secured thereto a pinion 9 for driving purposes, and meshing therewith is a spur or master gear 10, mounted on a crank-shaft 11, held by the supporting-bars 5.

Rising from the supporting-bars 5 is a gallows-frame 12, suitably braced and strengthened to compensate for the strain brought to bear thereon in the operation of the mechanism for propelling the hand-car. On the gallows-frame 12 bearing or cap bars 13 are secured and receive the shafts 14, fixed to gear elements 15, which are confined in longitudinal alinement between the upper portions of the gallows-frame or the bearing or cap bars. 95 The gear elements 14 comprise opposite head-disks 15^a, removably secured to gears 16 and also having attached thereto the yoked ends 17 of hand-bars 18. The gear elements are spaced apart from each other a sufficient dis- 100

- tance to operatively receive between them a double rack-bar 19, adjustably connected to a rod or connecting-bar 20, attached to the crank of the shaft 11, the lower end of the 5 double rack-bar being provided with a screw-threaded socket 21 to receive the upper screw-threaded extremity of the rod or connecting-bar 20. By this means the rod or connecting-bar is rendered adjustable to accommodate 10 the application of the operating mechanism to hand-cars now in use and also to take up wear of the several parts to insure a positive stroke or operation of the rod. It will be observed that the connecting rod or 15 bar is direct-acting with respect to the master-gear, and in the event that the gear elements meshing with the double rack-bar become worn the said elements may be reversed in view of the fact that they are secured solely 20 by screws 22 passing through the head-disks 15^a into the gears 16, which may be removed when desired. The yoked ends 17 of the hand-bars are countersunk in the head-disks of the gear elements, as at 23, and the terminals of said yoked ends loosely bear on the 25 shafts for the gear elements. This arrangement provides for a strong assemblage of the several parts and also insures a positive operation.
- 30 It will be understood that the platform of the car may be composed of boards or planks of the usual thickness adopted in hand-car constructions and arranged to provide the necessary or most platform-space possible 35 within a minimum surface area.
- The circular form of the gears which are held in continual mesh with the double rack-bar makes it possible to oscillate the latter without break or irregularity, and, further- 40 more, the head-disks confining the gears maintain the rack-bar in positive perpendicular position and obstruct the latter from moving laterally or sidewise, with material ad- vantage in the avoidance of lost motion by 45 impositive contact.
- It will be observed that operators grasping the opposite hand-bars and imparting motion to the gears and the disk-heads will cause the vertical reciprocation of the rack-bar and 50 connecting-rod attached thereto and result in a reliable rotation of the master-gear and the pinion connected to one of the car-axles. In the present instance the master-gear with 55 which the rack-bar directly operates is of materially greater diameter than the pinion on one of the car-axles held in continual mesh therewith, and by this means a regular rotation of the master-gear under normal speed conditions will cause a materially greater ro- 60 tation of the pinion and axle to which it is attached, with obvious advantages in pro- pulsion. Furthermore, the hand-car embodying the features of the present invention is of a light, strong, and durable nature, and 65 the same principle and construction might

be readily embodied in a construction of greater magnitude by varying the proportions, dimensions, and minor details.

Having thus fully described the invention, what is claimed as new is--

1. In a hand-car, the combination of a frame having wheeled axles, one of the axles carrying a pinion, a master-gear meshing with the pinion, a crank-shaft on which the master-gear is disposed, a gallows rising from the 75 frame, a connecting-rod attached to the crank of the shaft on which the master-gear is mounted, the connecting-rod being movable directly over the one face of the master-gear, a double rack-bar attached to the upper extremity of the connecting-rod, and prime operating means held by the gallows and engaging opposite sides of the rack-bar.

2. In a hand-car, the combination of a frame having wheeled axles, one of the axles having 85 a pinion thereon, a master-gear held by the frame and meshing with the pinion, a double rack-bar for operating the master-gear, and prime operating means supported above the frame and meshing with the opposite sides of 90 the rack-bar, the rack-bar and the said prime operating means being adjustable to take up wear.

3. In a hand-car, the combination of a frame having wheeled axles, a gallows supported 95 thereon, reversible gears held on the gallows, a double rack-bar movably disposed between and held in continual mesh with the gears, and driving mechanism for one of the axles and to which the said rack-bar is attached.

4. In a hand-car, the combination of a frame having wheeled axles, driving mechanism held by the frame and one of the axles, a double rack-bar attached to a part of the driving mechanism, reversible gears supported above 100 the frame and engaging the opposite sides of the rack-bar, heads movably attached to the gears, and hand-bars having inner yoked extremities engaging the heads.

5. The combination with a hand-car having driving mechanism for one of the axles, of a double rack-bar movably connected to a part of the driving mechanism, reversible gears held above the driving mechanism in close mesh with the opposite sides of the rack-bar, and means for operating the gears to actuate the rack-bar.

6. The combination with a hand-car having driving mechanism co-operating with one of the axles thereof, of a gallows thereon, gears having fixed shafts terminally held on the upper portion of the gallows, a double rack-bar movably disposed between the said gears and connected to a part of the driving mechanism, heads movably applied to opposite portions of the gears and operating to maintain the rack-bar in true vertical position, and hand-bars having inner yoked extremities let into the heads and provided with terminals engaging the shafts.

7. The combination with a hand-car having actuating mechanism for one of the axles thereof, of a double rack-bar connected to a part of the said mechanism, gears held above the mechanism and engaging opposite sides of the rack-bar, heads removably and rotatably mounted against opposite sides of the gears, and hand-bars connected to the heads.

8. In a hand - car, the combination of a wheeled frame having axles, one of the axles being provided with a pinion, a crank-shaft mounted in a portion of the frame, a master-gear centrally connected to the crank-shaft, a double rack-bar attached to the crank of the said shaft and movable over one side of the

master - gear, and gear elements held above the mechanism and engaging the opposite sides of the rack-bar, said gear elements confining the rack-bar between them and having projecting heads extending over the teeth of the rack-bar engaging the same to prevent contact therewith, of adjacent members. 20

In testimony whereof I have hereunto set my hand in presence of two subscribing witnesses.

PAUL J. KAMPER.
